Specification of Letters Patent. Patented Aug. 11, 1914.

Application filed March 6, 1913. Serial No. 752,319.

To all whom it may concern:

Be it known that I, WILLY STÜCKI, residing at Biel, Switzerland, have invented certain new and useful Improvements in Insoles, of which the following is a full, clear, and exact description, such as will enable others skilled in the art to which it appertains to make and use the same.

This invention relates to insoles for boots and shoes.

One of the objects thereof is to provide a neat and effective insole durably pervious to air.

Another object is to provide an insole of the above character which will not deteriorate in the presence of moisture.

Other objects will be in part obvious and in part pointed out hereinafter.

The invention accordingly consists of the features of construction and arrangement of parts which will be exemplified in the construction hereinafter set forth and the scope of the application of which will be indicated in the appended claim.

25 In the accompanying drawings wherein is shown a preferred embodiment of the invention:—Figure 1 is a bottom plan view of an insole, showing the wire webbing broken away at the heel to disclose the upper layer 30 of coarse fibrous webbing; Fig. 2 is an enlarged and exaggerated transverse section on line 2—2 of Fig. 1.

Similar reference characters refer to similar parts throughout the drawings and specification.

As conducing to a clearer understanding of the present invention, it may here be noted that insoles as usually constructed consist of a texture of soft vegetable or animal matter. 40 With such textures it has been found, in practice, that the considerable pressure and moisture to which the insoles are submitted have the effect, after a little use, of so matting the material together as to render the 45 same practically impervious to air and thus greatly to diminish the warmth of the insole and to render the same unsanitary. Insoles made in accordance with the present invention avoid this disadvantage and remain 50 fresh and sanitary.

Referring to the drawing, the insole is in-

dicated by 1 and comprises a layer or body of relatively fine wire webbing or fabric 2 surrounded by a binding of linen or other suitable tape 3, which when the article is 55 worn serves to protect both the interior of the shoe and the stocking of the wearer from the raw edges of the metal fabric. This binding is secured to the said fabric as by stitching 4. The metal fabric used is preferably woven from fine aluminum wire but other material such as zinc, tin or nickel covered steel wire may be employed or, in fact, any metal fabric having sufficient resistance to pressure and not affected by moisture. It is to be understood that the insole, if it should be preferred, may consist of more than one layer of metal fabric without departing from the scope of this invention. It is also desirable to cover one or both sides 65 of the metal fabric with a coarse fibrous fabric or webbing, such as jute or hemp, as indicated at 5, which cover is secured beneath the binding 3 as shown. The cover 5 should be as thin as is practicable and coarse 70 meshed.

In use the insole is worn in the usual manner within the boot or shoe, the coarse fibrous material being next the foot of the wearer.

From the foregoing it will be seen that 80 this invention is one well adapted to attain all the ends and objects hereinbefore mentioned in a thoroughly practical and hygienic manner and that as the fabric used is quite thin the insole will not inconvenience 85 the wearer by crowding the foot.

What is claimed and what is desired to be secured by United States Letters Patent is:—

An insole comprising a body portion consisting of but two layers having different 90 physical characteristics, one of said layers being composed of a metal fabric substantially non-corrodible by perspiration, and the other thereof, of coarse meshed fibrous material.

In testimony whereof I affix my signature, in the presence of two witnesses.

WILLY STÜCKI.
